UNITED STATES PATENT OFFICE.

KOSTA RELICH, OF NEW YORK, N. Y.

FUR KNIFE.

Application filed March 17, 1926. Serial No. 95,389.

This invention relates to improvements in fur knives and has particular reference to a safety razor blade holder for utilizing old safety razor blades for use in the fur cutting trade.

The primary object of the invention resides in a blade holder especially adapted for conveniently holding a safety razor blade so as to dispose the cutting edge in such novel manner as to facilitate the cutting of furs and skins, and in which the user is assured protection against injury when in use as the cutting edge of the blade is so positioned and guarded with respect to the handle as to prevent the fingers of the user from coming in contact therewith.

Another object of the invention is to provide a fur knife in which the cutting blade may be readily removed when becoming dull and a new one substituted therefor, so that the knife may be kept sharp at all times without necessitating the loss of time usually required for sharpening.

A further object of the invention is to provide a fur knife or blade holder which is simple in construction, easy to unlock or lock for the insertion of a new blade, and inexpensive of manufacture.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a side elevation of my improved fur knife.

Figure 2 is an edge view of the same.

Figure 3 is an enlarged vertical transverse sectional view on the line 3—3 of Figure 1.

Figure 4 is a longitudinal sectional view on the line 4—4 of Figure 1.

Figure 5 is a plan view of the holder in an open position.

Referring more particularly to the drawing, the reference numerals 10 and 11 respectively designate a pair of flat members or sections, each of which is identical in configuration and shaped to provide a handle portion 12 and a head portion 13. The sections 10 and 11 are hingedly connected together along one of the longitudinal edges of the handle portions, as at 14. The hinged joint is so constructed as not to project be-

yond the edge of the handle as clearly shown in Figure 1 of the drawing. One of the edges of each head extends at an angle with respect to the longitudinal edges of the handle portions and are designated as at 15, while the opposite edges of the members are curved and inclined to provide a point at the outer end of the members. A portion of the edges 15 are cut-away as at 17 so as to expose the cutting edge of the blade 18. The blade in the present instance is shown as of the Gillette type, but it will be appreciated that the sections may be slightly modified to accommodate other types of safety razor blades. The blade 18 is cut to such shape as to lie within the confines of the edges of the members but to allow the cutting edge to be exposed through the cut-away portions 17. The outer surfaces of the members adjacent the edges 15 and 16 are bevelled as at 19 to accommodate the fingers of the user when holding the device in the hand for cutting purposes and to impart a finished appearance thereto.

The blade 18 is supported upon the head 13 of the member 10 by spaced studs 20 which are punched from the material from which the member is formed and are of such length as to pass through the holes in the blade and against or into recesses 21 in the inner face of the member 11, when the two members are brought in co-acting position.

The head 13 of the member 11 carries a rotatable button 22 having a head 23 which is disposed in a recess on the exterior face of the member, and a head 24 which extends beyond the inner face and which head is provided with a flat face 25. The head 24 passes through a similar shaped opening 26 in the member 10 when the members are brought together, after which the button is given a slight rotation so as to seat the head 24 in a recess 27 provided in the outer face of the member 10 adjacent the opening 26.

From the foregoing description, it will be seen that I have provided a knife especially adapted for use in the fur trade for the purpose of cutting furs and skins, and which necessitates a sharp cutting blade. This blade is in the form of a used safety razor blade and which provides a relatively sharp cutting edge, which blade may be replaced when becoming dull.

What is claimed as new is:—

1. A knife comprising a pair of hingedly connected sections, a removable blade sup-

ported between said sections, and co-acting means between said sections engageable when said sections are in a closed position for locking said blade therebetween, said co-acting means including a turnable member carried by one of said sections for passage through an opening in the other of said sections and for seating engagement in a recess in the outer face of said last mentioned section.

2. A knife comprising a pair of sections hingedly connected along one of their longitudinal edges, a removable blade supported between said sections and having its cutting edge disposed in alignment with the certain meeting edges of said sections, said sections being cut-away to expose a portion of the cutting edge of said blade, the edges of said sections adjacent the edges of said plate being beveled, and co-acting means between said sections engageable when said sections are in a closed position for locking said blade therebetween.

3. A fur knife comprising a pair of sections shaped to provide handle portions and head portions, said sections being hingedly connected along one of the longitudinal edges of the handle portions so as to permit said section to be swung to lie one against the other with the outer edges in alignment, a cutting blade supported by the head portion of one of said sections and held thereon by the head portion of the other of said sections, and co-acting means between said sections for locking the same against swinging movement about said hinge, said co-acting means including a turnable headed member carried by one of said sections for passage through an opening in the other of said sections and for seating engagement in a recess in the outer face of said last mentioned section.

In testimony whereof I have affixed my signature.

KOSTA RELICH.
